RAZOR BLADE SHARPENER

Wilbur H. Parkison, Arlington, Va.

Application March 6, 1940, Serial No. 322,423

3 Claims. (Cl. 51—161)

This invention relates to sharpening devices, particularly to those adapted for sharpening double edged razor blades.

One object of the invention is to provide a device of the character described adapted for automatically reversing a blade by improved means operative without the need for cams or gears.

Another object of the invention is to provide a device of the nature set forth for sharpening opposite faces of opposite edges of a razor blade, with the utilization of simple improved means comprising a cylindrical member having a longitudinal slot opening directly communicating with the internal sharpening face of the member.

Another object of the invention is the provision of a device of the class alluded to whereby improved means cooperates with a blade holder that is rotatable in one direction to cause reversing of the blade for alternate sharpening of the opposite faces of the blade edges by direct coaction of the blade or of a freely revoluble blade carrier shaft rotatably mounted on the above mentioned holder, where said coaction takes place along the cylindrical surface of an internal sharpening face.

Another object of the invention is to provide a device of the nature set forth having an internal cylindrical face for simultaneously smoothing the opposite edges of a razor blade, in combination with a hone set into said surface for improved sharpening action on the blade in course of its normal movement along the cylindrical face.

Another object of the invention is the provision of an improved device of the type mentioned having a simple disc rotor carrying a rotary blade holder along an outer face of the rotor for sharpening the blade by wiping contact with the internal face of a cylindrical member from which the rotor is bodily removable and in which the rotor is journaled along the said internal face.

A further object of the invention is to provide a device of the character described wherein improved means having an internal cylindrical face, is formed with a longitudinal well coacting for reversal of the blade so that said face is adapted to act on opposite sides of the blade, and with the said well being adapted to contain a lubricant if desired.

Other objects and advantages of the invention will become apparent as the specification proceeds.

With the aforesaid objects in view, the invention consists in the novel combinations and ar-

rangements of parts hereinafter described in their preferred embodiments, pointed out in the subjoined claims, and illustrated in the annexed drawing, wherein like parts are designated by the same reference characters throughout the several views.

In the drawing:

Figure 1 is a vertical central cross sectional view showing a device embodying the invention, and with the blade and holder therefor located in reversing position.

Fig. 2 is a fragmentary view with parts in section of the rotor, showing an edge view of the blade holder.

Fig. 3 is an end view of said rotor.

Fig. 4 is a view of the blade holder in separated position, and in partially open position to receive a razor blade.

Fig. 5 is a vertical sectional view on the line 5—5 of Fig. 1, showing a plurality of blades and holders therefor to indicate the mode of operation of the device in different positions of the blade in its circuit.

Fig. 6 is a fragmentary sectional view showing the razor blade and its holder in course of being reversed.

Fig. 7 is a fragmentary sectional view on the line 7—7 of Fig. 1, with parts removed and showing a driving element that may be employed.

Fig. 8 is a longitudinal sectional view of a cylindrical member according to the invention, generally similar to that shown in Fig. 1, but modified to provide an oil reservoir to facilitate the sharpening action.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Generally described, the invention provides a cylindrical member having an internal face for smoothening or otherwise sharpening the opposite faces of both edges of a razor blade. Removably mounted within this member is a rotor which may seat directly against the sharpening face and which may carry one or more freely rotatable razor blade holders at points adjacent to the periphery of the rotor. In consequence each blade is flexed against the sharpening surface so

that both edges of the razor blade are pressed against said surface simultaneously. In order to present opposite faces of the razor blade for such sharpening action automatically and without the use of cams or gears, the invention provides a longitudinal slot opening in the surface of the cylindrical member, with a co-ordination such that not only is a clearance space furnished for reversal of the razor blade, but the longitudinal marginal portions of said opening may be utilized to effect the reversal. This coaction may result directly with either the razor blade or its freely rotatable holder, or both, and in any event, utilizes the spring action of the razor blade itself, whereby the leading edge of the latter is inherently caused to engage over the marginal edge of the longitudinal opening to thereby initiate the reversing action, which may then be completed by contact with a side of the blade or holder or both. As an aid to the occurrence of this action or as an alternative to the co-ordination mentioned, a spindle portion of the razor blade holder may directly frictionally engage the cylindrical sharpening surface or an extension thereof, so that the resultant torque which constantly causes the blade holder to turn becomes instantly effective when the leading edge of the blade enters the said longitudinal slot opening and may thus cause a reversing of the blade with or without direct contact of the cylindrical sharpening surface with the blade or its holder. If desired, a hone may be employed as a portion of the sharpening surface so arranged as to afford a substantially increased sharpening action. It will be appreciated that while the cylindrical member is preferably made of glass, it may also be constructed of other suitable materials which are capable of affording a perfectly smooth surface, and that it may be made in one or more pieces instead of as a one-piece structure herein disclosed.

Referring in detail to the drawing, 10 denotes a device embodying the invention. The same may comprise a generally cylindrical member 11 made of glass or other suitable material and which may have a separate or integral end wall 12, and a separate or integral offset portion 13 extending longitudinally thereof, and affording a compartment 14 having the mouth 15 thereof disposed along the internal cylindrical surface 16 of said member. It will be noted that the mouth 15 preferably affords an acute angle edge and that the chamber 14 diverges upwardly to thus afford a correspondingly divergent surface 17 for smooth wiping contact with an edge of the razor blade as hereinafter described. At its forward end the member 11 may be wholly open, and the offset portion 13 may terminate at 18 so that the internal cylindrical surface at this point may be uninterrupted for a reason that will hereinafter appear.

Removably disposed within the cylindrical member 11 is a rotor 19 comprising a plurality of like bearing elements or disks 20 that lie in parallel planes and are rigidly centrally interconnected by a hub or shaft 21 which may have a crank 22. The arrangement is such that when the rotor 19 is disposed within the cylindrical member 11, the disks 20 are fairly snugly journaled within the cylindrical highly smooth face 16 of the member 11, as will be readily perceived in Fig. 1, the rotor being inserted as far in as it will go, leaving the crank 22 projecting outwardly, clear of the cylindrical member, so that the crank

may be freely rotated while the cylindrical member is stationary.

Mounted upon the rotor 19 is a holder 23 adapted for securing any conventional double edge blade. This holder 23 is formed at its opposite ends with aligned spindles 24 journaled in very small openings 25 in the disks 20, these openings 25 being so relatively close to the periphery of said disks as to hold the razor blade in proper operative relation to the internal surface 16 of the cylindrical member. By way of illustration, and without being limited thereto, the holder 23 may comprise a main bar 26 having a pair of very slight projections 27 whose height is approximately equal to the thickness of a razor blade, these projections being adapted to enter the usual openings or holes by which the blade can be secured in a razor. It will be noted that one side of the bar 26 is formed with a cut out 28 in which the projections 27 lie, and in which a locking element or bar 29 may be received. This element 29 may be pivotally connected to the bar 26 at 30, and the latter may, moreover, be provided with a groove or recess 31 into which the free end of the element 29 may be readily slidably inserted in an edgewise manner for a closed position of the holder. Accordingly any razor blade 32 may be placed upon the bar 26 in engagement with the projections 27, whereupon the element 29 may be pivotally swung to closed position in alignment with the bar 26, so that said element 29 becomes locked at 31 and thus reliably secures the razor blade in position. It will be perceived that the holder 23 is quite thin so that it may permit the razor blade to approach quite closely in a flatwise manner against the cylindrical surface 16, and thus to obtain a substantial flexure of the razor blade with corresponding pressure of the edges thereof against said cylindrical surface. Preferably the holder 23 is also made quite narrow, although its width would appear to be of relatively lesser importance. This, however, will depend upon whether or not it be desired that the holder 23 be entirely clear of the cylindrical surface 16 at all times, or whether it be permissible for the edge portions thereof to enter the mouth 15 as suggested in Fig. 6.

For purposes of re-enforcement, or in order to provide a pulley like engagement with the cylindrical surface 16 to thus obtain such a torque as may be desired, the bar 26 may have trunnion-like portions 33 which may be substantially larger in diameter than the spindles 24. The arrangement in this regard may be such that the portions 33 may directly contact the cylindrical surface and may have a desired degree of frictional engagement therewith. If preferred, the wall of the cylindrical member at 18 may be slightly undercut as indicated at 34 to receive a strip of any suitable frictional material 35 which may be pasted or otherwise secured therein, to thus provide increased frictional contact with the roller portions 33, whereby rotation of the razor blade holder is initiated instantaneously with the approach of the leading edge of the blade to the mouth 15. At other points of the cylindrical member, the roller portions 33 may merely slide with a relatively low degree of frictional contact along the cylindrical surface 16.

At a suitable portion of the cylindrical surface 16, preferably remote from the chamber 14, there may be provided a hone 36 extending longitudinally of the cylindrical member and set into an undercut 37 thereof, but with one longitudinal

edge portion of the hone projecting slightly inward of the cylindrical surface 16 as indicated at 38. As a result, the degree of flexure upon the razor blade is substantially increased and the pressure of the blade edges against the cylindrical surface is correspondingly enhanced for a substantially greater sharpening action. In other words, as the leading edge of the razor blade makes contact with the hone, the adjacent cylindrical surface may be considered to have a substantially smaller radius so that the action above described directly occurs. This hone may consist of any suitable material, and accordingly the invention provides a combined smoothening and sharpening action upon the edges of a razor blade at both faces thereof, but with the smoothening action being relatively substantially greater than the honing action.

According to Fig. 8, the cylindrical member may be modified as shown at 11a with the provision at the open end thereof of an offset portion 39 so that the offset 13a may constitute a reservoir to contain a small quantity of very thin oil that may be suitable to substantially increase the sharpening action on the razor blade. In other respects, the structure may be substantially like that of Fig. 1, and it will be noted that the modification involves inverting the cylindrical member and closing the end of the offset portion thereof.

The manner of using the invention will now be briefly described. It is intended that the rotor 19 shall be rotated continuously in a clockwise direction as indicated by the arrow 40 with the blade holder 23 moving along and in very close proximity to the cylindrical surface 16, and with the blade 32 longitudinally flexed thereagainst so that opposite edges of the blade simultaneously contact the said cylindrical surface. The flexure mentioned stores a spring action which is relieved when the razor blade moves to the mouth 15, thereby causing the leading edge of the blade to move upward and to follow along the surface 17 with a diminished pressure which will not damage the edge of the blade, but it will be sufficient to initiate turning of the blade and its holder. As the clockwise motion continues, the rotation may be completed by a side of the blade or of the holder contacting the adjacent edge of the mouth 15 and as rotation progresses, the position of the blade and its holder will return to normal but in reversed relation. It will be noted that the struc-

ture involved requires that the edge at the mouth be relatively thin. However, if the roller action is employed as indicated at 33 and 35, reversing rotation of the blade and its holder may occur independently of engagement at the mouth 15, and in consequence the edge of the latter may be relatively thick as preferred, and the slope at 17 might be omitted. As rotation of the rotor 19 continues, the opposite edges of the blade are subjected to the honing action of the element 36. It will thus be perceived that I have provided a device which is extremely simple and practical and highly adapted for reliable and convenient use.

I claim:

1. A device for sharpening double edged razor blades including a member having an internal cylindrical sharpening surface interrupted by a longitudinal opening, a rotor coaxially journaled in said member, and means comprising a freely rotatable blade holder journaled on said rotor adjacent to the periphery thereof and having an axis parallel to that of said member, said means having roller portions having frictional engagement with a wall portion of the member to thus cause the blade holder to make a one-half turn at said opening.

2. A device including a member having a smooth glass-hard internal cylindrical surface, and a honing element having a greater sharpening quality than said surface set into a portion of the wall of the member for acting on the edges of a razor blade which is pressed against said surface and moved therealong and along the honing element whereby the edges of the blade are alternately honed and smoothened, said honing element being flush at one edge with the said surface and being raised at an opposite edge to thus afford a curvature having a radius less than that of the said surface of the member.

3. A device having a member having an internal cylindrical sharpening surface, a rotor axially journaled in said member, a blade holder freely rotatably mounted on said rotor adjacent to a periphery thereof, said member having a longitudinal chamber communicating with said surface by a longitudinal opening, said chamber affording a space for a turning movement of the blade holder and of a blade held thereby and constituting an oil reservoir for lubrication of the blade.

WILBUR H. PARKISON. 50
